ROTATABLE MAGAZINE TABLE

Gregory R. Lange, 1247 Diana Ave.,
Anaheim, Calif. 92805

Filed Nov. 12, 1968, Ser. No. 14,404

Term of patent 14 years

Int. Cl. D6—01

U.S. Cl. D33—14

FIG. 1

FIG. 2

FIG. 1 is a perspective view of the present rotatable magazine table; and

FIG. 2 is a reduced, side elevational view of the rotatable magazine table of FIG. 1.

The encircling railing and base are continuous around the table and the side surface not shown is the same in appearance as the side surface shown.

I claim:

The ornamental design for a rotatable magazine table, as shown and described.
